UNITED STATES PATENT OFFICE.

BLASIUS KOVACIC, OF EAST PITTSBURG, PENNSYLVANIA.

INK-WELL.

No. 866,486.

Specification of Letters Patent.

Patented Sept. 17, 1907.

Application filed May 3, 1907. Serial No. 371,588.

To all whom it may concern:

Be it known that I, BLASIUS KOVACIC, a subject of the King of Hungary, residing at East Pittsburg, in the county of Allegheny and State of Pennsylvania, have 5 invented certain new and useful Improvements in Ink-Well, of which the following is a specification, reference being had therein to the accompanying drawing.

This invention relates to improvements in ink wells, 10 and the invention has for its object to provide positive and reliable means for effecting the closing of the opening of an ink well, should the same be accidentally tilted or upset.

My improved ink well consists of a receptacle having 15 a sliding lid for closing the pen opening of the ink well, the lid being normally retained in a closed position by a spring, and held in an open position by a gravity plunger. The lid is provided with a spring-held element in the form of a ball for closing the pen opening 20 of the well, when the lid is in a closed position.

The detail construction of my invention will be hereinafter more fully described and then specifically pointed out in the appended claims; and referring to the drawing forming part of this specification, like 25 numerals of reference designate corresponding parts throughout the several views, in which:—

Figure 1 is a perspective view of the ink well, the lid thereof omitted, Fig. 2 is a perspective view of the lid, Fig. 3 is a vertical sectional view of the ink well, 30 the lid and plunger thereof being omitted, Fig. 4 is an elevation of a gravity plunger used in connection with the well, Fig. 5 is a sectional view of the lid of the ink well, Fig. 6 is an elevation of a spring and closure used in connection with the lid, Fig. 7 is a fragmentary 35 sectional view of the ink well illustrating the lid in an open position, Fig. 8 is a similar view of the well illustrating the lid in a closed position.

To put my invention into practice, I construct my improved ink well in the form of a receptacle 1 having 40 a bottom 2 of sufficient thickness and weight to insure stability in position of the ink well. The top of the receptacle is closed by a plate 3 having a countersunk portion 4 and provided with guide ways 5 for a lid 6. The countersunk portion 4 of the plate 3 is provided 45 with a beveled pen opening 7.

The lid or closure 6 is adapted to slide in the guide ways 5, and is provided with a slotted extension 8 for the reception of the upper end of a spring 9, secured to one side of the receptacle 1, as at 10. The spring 9 is 50 adapted to normally hold the lid in a closed position. The opposite end of the lid 6 is provided with a vertically-extending tubular portion, the upper end of which is closed by a screw 15 threaded therein, thereby forming a pocket for a spring 12 and a pen-opening 55 closing element, such as a ball or other spherical body 14, the latter being adapted to rest in the beveled pen-

opening to close it when the lid is in its closed position, being held therein by the spring 12.

To retain the lid 6 in an open position, I provide the receptacle at a suitable point below the lid 6 with a 60 vertically disposed sleeve 16, said sleeve being suitably secured in the bottom of the receptacle and in the countersunk portion 4 of the plate 3. In the sleeve 16 is mounted a gravity plunger 17 having tapering ends 18 and 19, the former being adapted to engage recesses 65 20 or 21 formed in the under face of the lid 6, while the latter is positioned and guided in a plug 22 threaded in the lower end of the sleeve 16, said plug having a central passageway through which the end 19 extends.

The position of the lid or closure for the ink-well, 70 when the latter is in use, is shown in Fig. 7 of the drawing, wherein the lid 6 is held in its outer or open position by the tapering end 18 of the gravity plunger 17 extending into the recess 20 of the lid 6 against the tension of the spring 9. When the ink well is raised or 75 tilted, the plunger 17 descends by gravity a sufficient distance to release the lid 6, and allow the spring 9 to close said lid. The ball 14 is immediately seated in the beveled pen opening 7, thereby sealing it. When the ink well is righted, the tapering end 18 of the plunger 80 17 engages in the recess 21 of the lid and holds the lid in a closed position. To open the lid it is necessary that the ink well be raised to allow the plunger to release the lid, at which time the lid can be opened 85 against the tension of spring 9 and the tapering end 18 of the plunger 17 allowed to pass into the recess 20 of the lid 6.

The beveling of the pen opening 7 permits the element 14 to readily move into and out of said opening 90 when the lid 6 is moved.

It will be apparent from the illustration of my invention that I have devised an ink well that can be filled in the ordinary manner, but which, when accidentally upset or tilted, cannot precipitate the ink or writing fluid therefrom.

The ink well is preferably constructed of metal having non-corrosive qualities, and is capable of being ornamented and finished to present a neat appearance.

What I claim and desire to secure by Letters Patent, 95 is:—

1. The combination with an ink-well having a pen opening, of a normally-closed sliding closure for said opening, and means carried by the well for positively retaining the closure in either open or closed position, the position of the well controlling the action of said means.

2. The combination with an ink-well having a pen-opening, of a closure for said opening, said closure being movable in a direction laterally of the opening, said closure being normally in closed position, and means carried by the well for retaining the closure in either an open or closed position, the position of the well controlling the action of said means.

3. The combination with an ink-well having a pen-opening, of a spring-closing closure for said opening, said clo-

- sure being movable in a direction laterally of the opening, and gravity-release means carried by the well for retaining the closure in an open position, the position of the well controlling the action of said means.
- 5 4. The combination with an ink-well having a pen-opening, of a spring-closing closure for said opening, said closure being movable in a direction laterally of the opening, and means carried by the well for retaining the closure in an open position, the release of said means being controlled by the position of the well.
- 10 5. An ink well having a closure for its pen-opening, a spring for placing a tension on said closure and means for retaining said closure in an open position, against its spring-tension, the operative position of said means being controlled by the position of the well.
- 15 6. An ink-well having a laterally-movable closure for its pen-opening, and means whereby the closure, when in its open position, will be automatically closed upon an upsetting movement of the well, said means retaining the closure in either an open or closed position.
7. An ink well consisting of a receptacle, a top plate carried thereby and having a countersunk portion provided with a beveled pen opening, a spring held lid slidably mounted in said countersunk portion, a spring-pressed element carried by said lid for closing said opening, a sleeve mounted in and extending through said receptacle, and a gravity plunger arranged in said sleeve for holding said lid in open or closed position.
8. An ink well consisting of a receptacle having a pen opening formed therein, a spring-pressed lid slidably mounted upon said receptacle, a spring pressed element for closing the opening of said receptacle, and a gravity plunger mounted in and guided by said receptacle for holding said lid in open or closed position.
- In testimony whereof I affix my signature in the presence of two witnesses.
